UNITED STATES PATENT OFFICE

MARCEL PAUL DURAND, OF ST. GERMAIN-EN-LAYE, FRANCE

SPINDLE DRIVE

Application filed June 26, 1929, Serial No. 373,826, and in France August 17, 1928.

This invention concerns improvements in means for driving the spindles of spinning machines and the like of the kind wherein each spindle is tangentially driven by a belt at two diametrically opposite points. In accordance with the invention in an arrangement of this character the belt is adapted to be normally forced on to the spindles by means of pairs of pressure rollers, each pair of rollers acting radially of one spindle. This method of driving offers several advantages. For example, each spindle has an individual positive drive without radial pressure on its bearing, the mechanism being suited in particular to the use of a single simple spring, not fixed to the machine frame, ensuring such balanced drive whatever irregularities there may be in the belt-thickness. Moreover, the mechanism is readily adapted for uncoupling and braking each spindle individually.

Other features will appear from the following description which relates, by way of example, to a bank of vertical spindles. Fig. 1 is an elevation and Fig. 2 a sectional plan (the section being taken on line 2—2 in Fig. 1) of the driving belt common to a set of spindles and its tensioning and longitudinal compensating arrangement. The belts adapted to be driven from the same drum or shaft are also shown.

Fig. 3 is an elevation and Fig. 4 a plan of the individual spindle arrangement in coupled position.

Figs. 5 and 6 show in similar fashion the arrangement when uncoupled and braked.

Figs. 7 and 8 are diagrammatical views of modifications in certain details.

1 and 1' represent the end-supports of the frame, the intermediate supports and thread-working apparatus of which are not shown. The cylindrical pulleys 2 of one rectilinear set of spindles are disposed between the portions of belts 3 or 3' which touch them tangentially at diametrically opposite points (Fig. 2). The belt 3, driven by a drum 4, passes over a roller 5 carried by 1 to drive one set of spindles, and the belt 3' driven by the same drum and passing over a roller 5' drives the second set shown. At the opposite end of the frame the belt 3 passes over

a roller 6 and return roller 7 carried by a carriage 8 sliding on a guide 9, this allowing regulation of the belt by manual operation of a screw 10 engaging a nut 11 rigid with the carriage or by automatic operation of a chain 12 running over roller 13 and carrying weight 14. A similar arrangement is provided for the belt 3'.

A modification is, however, shown in Fig. 8 in connection with the belt 3'. If the carriage 8 is moved from the position shown in full lines to that indicated in dotted lines, i. e. a distance b of, for example, 0.2 metre, the carriage in acting on two portions of belt produces a longitudinal compensation of 0.40 metre. If now, by bringing the carriage back and passing the belt over the roller 15 on the support 1' as shown for the belt 3' the subsequent adjustment by the carriage will act on four portions of the belt to permit a compensation of 0.80 metre which, added to the previous adjustment, gives a total adjustment of 1.20 metre for a carriage movement of 0.20 metre.

Clearly if it is not desired to have a large compensation or if it is required to place the two sets of pulleys at the same height one belt only need be employed. In this case the two outer portions will pass over the drum 4, the two inner portions over the rollers 5, 5' and at the other end of the frame loops are formed as indicated already for belt 3. The two carriages could be combined and the roller 15 omitted.

If it is desired to use only one drive shaft 16 and drive-pulley 17 for a frame too long to allow the employment of a single belt, a drum 4' may be used at the top to drive one or two other belts 18, 18' as shown in Fig. 8 extending in a direction opposite to the belts 3, 3', the arrangement being repeated if desired (as indicated at 4'') to allow of further sets of spindles being driven at different heights.

For coupling the pulleys 2 each spindle is provided with its individual mechanism supported, for example, by a plate 19 rigid with the bearing 20 carrying the spindle 21. Two spindles 22, 22' rigid with 19 receive respectively levers 23, 23' carrying idle rollers 24,

- 24' drawn towards one another by an arched spring 25, the two portions of the belt 3 touching the pulley 2 being thus held against said pulley by the rollers 24, 24' to drive the same 5 in a perfectly balanced manner without any radial pressure on the bearing. The spindles of rollers 24, 24' receive a radial pressure but this occurs under the best conditions of working.
- 10 The uncoupling is effected by simultaneous separation of the rollers 24, 24'. For this purpose the levers 23, 23' carry arms 26, 26' connected together by a rod 27 and link 28, the latter being adapted to be acted upon by 15 a finger 29. This finger is disposed at the end of a shaft 30 passing through a boss 31 rigid with 19 and carrying a control lever 32 provided with a mass 33 sufficiently heavy to hold the arrangement in the coupled position 20 when on the left of the vertical (Fig. 3) or in the uncoupled position when on the right (Fig. 5), the rollers being then separated from the belt. This separation alone is not sufficient to stop the pulley 2 completely, and 25 the levers 23, 23' are therefore provided with lugs 34, 34' adapted to brake the pulley 2 when the rollers are separated to remove the pressure on the belt. There is thus obtained a braking and uncoupling that is rapid in action and requiring only a small effort (the displacement of weight 33 to the right from a position only slightly to the left of the vertical) which may, if desired, be supplied by any 30 security device on the frame (stop motion, calibrating device or the like) to obtain automatic stoppage of the individual spindle in incorrect conditions of operation.
- It is clear that the form of construction given is only described by way of example 40 and that it may be modified without exceeding the scope of the invention as defined by the following claims.

What I claim is:—

1. A spindle drive constituted by a pulley 45 member on the spindle, a belt engaging said pulley at two diametrically opposite points, a pair of pressure rollers acting radially of the pulley at diametrically opposite points, and means for pressing said rollers on said belt.
2. A spindle drive constituted by a pulley member on the spindle, a belt engaging said pulley at two diametrically opposite points, a pair of pressure rollers acting radially of the pulley, means for forcing said rollers against said belt, and means for shifting said rollers to uncouple the drive.
3. A drive as claimed in claim 2, having 55 brake means acting on the pulley when the rollers are moved to the uncoupling position.
4. A drive arrangement for a bank of spindles, comprising a pulley on each spindle, a belt engaging each pulley at two diametrically opposite points, a pair of pressure

rollers associated with each spindle and acting radially thereof on the belt at diametrically opposite points, and a belt-adjusting carriage.
